UNITED STATES PATENT OFFICE.

AUGUST SIEGEL, OF CHARLOTTENBURG, AND FRANS GOLDSTEIN, OF BERLIN, GERMANY, ASSIGNORS TO GENERAL ELECTRIC COMPANY, A CORPORATION OF NEW YORK.

CENTRIFUGAL PUMP.

1,063,611.

Specification of Letters Patent.

Patented June 3, 1913.

Application filed June 24, 1910. Serial No. 568,653.

To all whom it may concern:

Be it known that we, AUGUST SIEGEL and FRANS GOLDSTEIN, subjects of the Emperor of Germany, residing, respectively, at Charlottenburg and Berlin, Germany, have invented certain new and useful Improvements in Centrifugal Pumps, of which the following is a specification.

The invention relates to centrifugal pumps used for exhausting air, gases, vapors, etc., from large chambers, such for example, as condensers, and more especially to means for starting such pumps in an improved and efficient manner.

In the accompanying drawing illustrating one mode of applying the invention, Figure 1 is an elevation showing the general arrangement of the apparatus, some of the parts being in section; and Figs. 2 and 3 show modifications of certain parts of the apparatus.

In installations where throwing air pumps are used to exhaust condensers or other large chambers, a considerable quantity of a special throwing medium not necessary for ordinary operation has to be supplied to the pump when starting up before a degree of vacuum is created sufficient to automatically draw the regular throwing medium into the pump. This special or supplementary medium is usually water under pressure. The present invention reduces to a minimum the consumption of the supplementary or auxiliary starting medium, thereby effecting a material saving in the operation of the apparatus. The starting medium is not only in many cases difficult to obtain but it is also difficult to remove and is the cause of considerable expense.

In our invention at least one cut-off member is arranged between the centrifugal air pump and the region to be exhausted so that the pipe or pipes connecting the two can be shut off in such a manner that when the pump is being started, the gases to be drawn off cannot pass to its suction chamber or can do so only gradually.

In order to obtain the degree of vacuum requisite to automatically supply the pump with throwing water with the arrangement just described, it is only necessary after the pump has been brought to the desired speed of rotation to furnish a small quantity of water from the auxiliary source of supply.

When the desired vacuum is established, the supply of starting medium is shut off and the regular throwing water connection is opened. The gases and vapors are then sucked from the condenser through the connecting pipe or pipes by the action of the throwing water, said pipe being opened to a limited extent until the suction has produced such a degree of vacuum in the condenser that the pipe can be opened to the degree desired for regular operation without endangering the automatic suction of the throwing water by the pump.

To reduce the quantity of starting water to a minimum and to utilize as small a degree of vacuum as possible for drawing in the throwing water, the column of fluid which is at rest in the throwing water conduit and has to be set in motion by said vacuum, is made as short as possible. To secure these important results, the starting water under pressure is introduced into the throwing water supply pipe as near the beginning of said pipe as possible, so that the starting water before entering the pump will force the column of fluid in said pipe ahead of it, thereby bringing the contents of the pipe into movement in a direction favorable for subsequent suction by the pump. By supplying the starting water to the throwing water suction pipe in this manner, no more water is used than if it were introduced directly into the pump, since the water already in the suction pipe which is forced forward is used as throwing or starting water and assists in producing the desired vacuum.

Referring to the drawing, the centrifugal throwing air pump 4 is driven by any suitable motor and is connected by the pipe or conduit 5 to the condenser 6 from which it removes gases and vapors. The flow through the pipe 5 is controlled by a valve 7 provided with a small opening or by-pass 8 in the valve disk which, when the valve is closed, permits only a small quantity of gas or vapor to be drawn from the condenser. The throwing water is taken from the tank or well 9 having an overflow 10 to prevent flooding. The throwing water passes from the well through the pipe 11 to a cooler 12 of any approved construction and from the cooler through the pipe 13 to the inlet of the pump 4. The discharge

from the pump passes through the pipe 14 to the well, the water replenishing the supply in the well and the air passing off.

The starting water is supplied from any suitable source by a pipe 15 which joins the pipe 11 as close to the well as possible. A three-way valve 16 controls the flow from either the pipe 11 or the pipe 15 to the cooler 12, pipe 13 and the pump 4.

10 Instead of providing the valve 7 with an opening 8, the valve can be somewhat loosely fitted or it can be provided with some kind of a stop or indicating device which will permit a known small opening thereof adapted to the conditions. Or these devices and the opening 8 can be omitted and a bypass 17, Fig. 2, arranged around the valve 7 with a valve 18 in said by-pass to regulate the size of the passage or opening at a given point through which air, etc., must pass from the condenser to the pump when the valve 7 is closed. This small opening in the by-pass can also be obtained by inserting a perforated plate 19, Fig. 3, between 25 the flange 20 on the pipe 5 and the flange 21 on the by-pass pipe 17.

With the last arrangement, it is only necessary when connecting the pump to another condenser or when adopting other conditions of operations to replace the plate or disk 19 by another having a suitably different perforation in order to obtain the best operating conditions for these particular cases.

35 The method of operating the apparatus when starting the pump is as follows:—The valve 7 is closed either before starting the pump or during starting or after the pump has been brought to the desired speed of rotation. The three-way valve 16 is then so adjusted that it shuts off the pipe 11 and supplies starting water from the pipe 15 to the pump through the pipe 13. The starting water flows into the pump impeller and 40 speedily creates a vacuum sufficient to draw throwing water from the well 9 through the parts 11, 12 and 13. When said vacuum is established, the valve 16 is shifted to shut off the pipe 15 and connect the pipe 11 to 45 the pump. The efficient suction of the throwing water from the well 9 by the least possible vacuum in the pump is facilitated by making the junction of the pipe 15 with the pipe 11 as close to the well 9 as possible, 50 so that the water and air in the cooler 12 and the pipe 13 are set in motion in a direction favorable to the suction of the water from the well 9. Hence only a small quantity of fluid has to be accelerated by the 55 vacuum. This vacuum is formed in a very short time, since by reason of the small opening in the valve disk or in the by-pass, only a small quantity of air can be sucked out of the condenser 6. The operation of 60 the pump is then continued with the regular

throwing water, the valve 7 being closed, until such a vacuum is formed in the condenser that said valve can be opened without causing the vacuum in the pump to fall so much that the throwing water cannot 70 be drawn into the pump by it. It is, moreover, immaterial to the operation by this method whether the small opening for permitting a restricted flow is introduced between the condenser and the pump before or 75 during the starting of the pump. Thus, for example, a shut-off member or valve, such as 18, may be placed in the by-pass 17, which valve is not opened until after such a vacuum is established in the pump that a 80 small quantity of air, vapor, etc., may be sucked through said opening without impairing the vacuum in the pump to any objectionable extent.

In accordance with the provisions of the 85 patent statutes, we have described the principle of operation of our invention, together with the apparatus which we now consider to represent the best embodiment thereof; but we desire to have it understood that the 90 apparatus shown is only illustrative, and that the invention can be carried out by other means.

What we claim as new and desire to secure by Letters Patent of the United States, 95 is,—

1. In combination, a condenser chamber, a throwing pump for exhausting the chamber, a well, a conduit through which throwing water is drawn from the well into the 100 pump by suction, a starting water conduit connected to the first conduit at a point adjacent to the well for supplying water under pressure to set the contents of the first conduit in motion toward the pump, a valve means for controlling the flow through the two conduits, a conduit leading from the pump discharge to the well, a conduit connecting the pump with the chamber, and valve means in the last mentioned conduit including a device having an area less than the full opening of said conduit for permitting a flow from the portion of the conduit at one side of said means to the portion at the opposite side thereof when said 110 means is closed.

2. In combination, a condenser chamber, a throwing pump for exhausting the chamber, means for supplying starting and regular throwing water to the pump, a connection between the pump and the chamber, a valve in said connection, and a by-pass around said valve having an area less than the full valve opening for permitting a flow from one side of the valve to the other when 125 said valve is closed.

3. In combination, a chamber, a throwing pump for exhausting the chamber, a conduit for supplying throwing water from a suitable source to the pump, a conduit con- 130

nnected to the throwing water conduit adjacent its inlet end for supplying starting water to the pump under pressure, means controlling the flow through said conduits, 5 a connection between the pump and the chamber, and means for varying the effective area of said connection.

4. In combination, a condenser chamber, a throwing pump for exhausting the chamber, a conduit supplying throwing water from a suitable source to the pump, a conduit connected to the throwing water conduit near said source for supplying starting water to the pump under pressure, valve 10 means for controlling the flow through said conduits, a connection between the pump and the chamber, and valve means in said connection including a device having an area less than the full valve opening for 15 permitting a flow from one side of said valve means to the other.

5. In combination, a chamber, a throwing

pump for exhausting the chamber, a well, a conduit supplying throwing water from the well to the pump, a cooler arranged in said conduit, a starting water conduit connected to the first conduit between the well and the cooler, a three-way valve at the junction of said conduits for controlling the flow there-through, a conduit leading from the pump 25 discharge to the well, a conduit connecting the pump to the chamber, and a valve in said conduit provided with by-pass means having a flow area less than the full valve opening for permitting a flow from one side 30 of the valve to the other.

In witness whereof, we have hereunto set our hands this 8th day of June, 1910.

AUGUST SIEGEL.
FRANS GOLDSTEIN.
